UNITED STATES PATENT OFFICE

2,538,304

TROUSER CUFF

Abe A. Fogley, Scranton, Pa.

Application October 5, 1948, Serial No. 52,827

1 Claim. (Cl. 2—232)

1

This invention relates to new and useful improvements and structural refinements in the manufacture of trousers, and the principal object of the invention is to facilitate substantial savings in material from which trousers are made.

In particular, the instant invention pertains to the formation of trouser cuffs, and an important feature of the invention involves the formation of the cuff in such manner as to eliminate the conventional folding and doubling of material in the lower portion of the trouser leg resulting in the formation of the cuff.

Conventional trouser cuffs are, of course, formed by first doubling the lower end portion of the trouser leg under itself and then folding the doubled portion outwardly and upwardly upon itself so that actually four thicknesses of material are present in the cuff below the intermediate single thickness of the trouser leg.

The instant invention proposes to eliminate this unnecessary waste of material by doubling the lower end portion of the trouser leg upon itself outwardly and upwardly, and thereupon folding the doubled portion upon the intermediate portion of the trouser leg, so that only three thicknesses of material are present in the cuff, including the material thickness of the trouser leg itself.

In addition, the invention proposes to eliminate the conventional practice of providing a perimetric seam in the cuff, whereby the formation of the cuff is substantially simplified in addition to the material saved.

With the above more important objects and features in view, and such other objects and features as may become apparent as this specification proceeds, the invention consists essentially of the arrangement and construction of parts as illustrated in the accompanying drawings, in which:

Figure 1 is a fragmentary side elevational view of a trouser leg before the cuff is formed;

Figure 2 is a fragmentary side elevational view of the trouser leg with the cuff formed thereon;

Figure 3 is a cross sectional view, taken substantially in the plane of the line 3—3 in Figure 1;

Figure 4 is a cross-sectional view, taken substantially in the plane of the line 4—4 in Figure 2; and

Figure 5 is a cross-sectional view, taken substantially in the plane of the line 5—5 in Figure 2.

Like characters of reference are employed to 55 necessary.

designate like parts in the specification and throughout the several views.

Referring now to the accompanying drawings in detail, the reference character 10 indicates a 5 trouser leg generally, having what may be called an intermediate portion 12 and a lower end portion 14. (See Figure 1.)

As is best shown in Figure 1, the lower end portion 14 of the trouser leg is separated from the intermediate portion 12 by a fold line 16, while the lower end portion 14 itself is intended to be doubled upon itself along a fold line 18.

In forming the trouser cuff, the usual inner seam 20 of the trouser leg is discontinued somewhat above the level of the fold line 16 as indicated at 22, and an outside seam 24 is provided so as to constitute a longitudinal continuation of the inner seam 20 down to the lower edge 26 of the cuffless trouser leg.

20 In forming the improved cuff, the lower end portion 14 of the trouser leg is first doubled outwardly and upwardly upon itself along the fold line 18, whereupon the lower portion so doubled is folded outwardly and upwardly upon the intermediate portion 12 so as to form the cuff 28 best shown in Figures 2 and 5.

By virtue of this formation the cuff 28 is constituted by only three thicknesses of material shown in Figure 5, this including the single thickness of material in the trouser leg itself.

30 Inasmuch as the outer surface 30 of the finished trouser cuff is constituted by a continuation of the inner surface of the trouser leg, it is necessary to provide the outer seam 24 as described in place of continuing the inner seam 20 to the lower edge 26 of the trouser leg.

The customary stitching of the double lower leg portion along the entire perimeter of the trouser leg is eliminated, but if desired, the 40 doubled and folded seams 24 may be "tacked" or stitched to the intermediate leg portion 12 as indicated at 32 in Figure 4.

Needless to say, after the material has been doubled and folded upon itself as above described, the finished cuff should be pressed in the conventional manner.

It may be added that the cuff formed in accordance with this invention is easily adjustable as to length of trouser leg, since the customary perimetric stitching in the cuff is not present.

It is believed that the advantages and use of the invention will be clearly apparent from the foregoing disclosure and accordingly, further description thereof at this point is deemed un-

While in the foregoing there has been shown and described the preferred embodiment of this invention, it is to be understood that minor changes in the details of construction and arrangement of parts may be resorted to without departing from the spirit and scope of the invention as claimed.

Having described the invention, what is claimed as new is:

In a trouser leg, a lower end portion and an intermediate portion separated from the lower end portion by a perimetric fold line, said lower end portion having an outside seam extending upwardly from its lower edge to a point on the intermediate portion spaced above said fold line by a distance equal to substantially one half the width of the lower end portion, said intermediate portion having an inner seam extending upwardly from and constituting a continuation of the

10

5

upper end of said outside seam, the lower end portion being doubled upwardly and outwardly upon itself and being turned upwardly and outwardly along said fold line upon the intermediate portion, whereby to provide a cuff having no more than three thicknesses of material and having its upper edge disposed substantially at the level of the junction of the inner and outer seams.

ABE A. FOGLEY.
